PAGE 2

FIG. 3

FIG. 4

FIG. 5

FIG. 6

FIG. 7

FIGURE 1 is a perspective front view of a cabinet for electrical equipment or the like, showing my new design; FIGURE 2 is a perspective rear view thereof; FIGURE 3 is a front elevation view thereof; FIGURE 4 is a rear elevation view thereof; FIGURE 5 is a top plan view thereof; FIGURE 6 is a left elevation view thereof; and FIGURE 7 is a right elevation view thereof.

I claim:

The ornamental design for a cabinet for electrical equipment or the like, as shown.
